UNITED STATES PATENT OFFICE.

HERMANN CONRAD, OF NEUSTADT, HAARDT, GERMANY.

PLAN SIFTING MACHINE.

Application filed November 16, 1921. Serial No. 515,727.

To all whom it may concern:

Be it known that I, HERMANN CONRAD, a citizen of the German Republic, and residing at Neustadt, Haardt, Germany, have 5 invented certain new and useful Improvements in Plan Sifting Machines, of which the following is a specification.

This invention relates to an improved freely oscillating plan sifting machine having 10 two superposed sieve-boxes and a driving-disc arranged horizontally between the latter, and its novelty consists in connecting said driving-disc by means of crank-pins to said sieve-boxes and balancing it around its oscillatory centre, that is the gravity centre 15 of the whole driving-disc, behind centre lying exactly in the middle between said crank-pins, one of said crank-pins lying in the central axis of said driving-disc and 20 the other at 180° thereto relatively to said oscillatory centre.

The accompanying drawing shows the improvement:

Figs. 1 and 2 are respectively a side view 25 and a front view of the plan sifting machine,

Fig. 3 is a plan view of the same,

Fig. 4 is a vertical section through the driving-disc mechanism,

Fig. 5 is a plan view of the driving-disc.

The freely oscillating plan sifting machine, without a separate fly-weight, comprises two sieve-boxes *c* and *d* suspended above one another from pendulums *a* and *b* 35 in such a manner that the upper sieve-box *c* suspended from the pendulums *a* can oscillate between the pendulums *b* of the lower sieve-box *d*, the two sieve-boxes being in communication with one another through 40 flexible tubes.

A crank-disc *f* arranged horizontally between said sieve-boxes and forming at the same time a driving-pulley, effects the oscil-

lation of said sieve-boxes by the attachment of its loose crank-pins *h*, *i* to the centre of 45 the bottom of the upper sieve-box and to the centre of the top of the lower sieve-box respectively, one of said crank-pins lying in the central axis of said crank-disc and the other at 180° thereto relatively to the 50 oscillatory centre *k*, the crank-disc being balanced or eccentrically weighted around said oscillatory centre and capable of being driven by means of a belt *n* guided over rollers *m* which are mounted in brackets *l* 55 suspended from the upper sieve-box *c*.

The particular advantage of the improvement lies in the fact that, while omitting a separate flyweight used with the hitherto known plan sifting machines and necessitating a specially strong frame, the oscillation of the sieve-boxes is attained in a reliable manner and in a uniform way simply by means of a crank-disc arranged between said sieve-boxes and the crank-pins of which 60 are attached to the latter, whereby the utility of the machine is increased, its construction is simplified, and costs are saved.

What I claim, is:—

In a plan sifting machine, in combination, 70 two oscillatory sieve-boxes, a belt-driven crank-disc horizontally arranged between the latter and balanced around its oscillatory centre, and crank-pins on said crank-disc attached to said sieve-boxes, one of 75 said crank-pins lying in the central axis of said crank-disc and the other at 180° thereto relatively to said oscillatory centre, substantially as and for the purpose set forth.

In testimony whereof I have hereunto set 80 my hand in the presence of two subscribing witnesses.

HERMANN CONRAD.
